UNITED STATES PATENT OFFICE.

DON CARLOS TRAVIS, OF KENOSHA, WISCONSIN, ASSIGNOR TO SIMMONS COMPANY, OF KENOSHA, WISCONSIN, A CORPORATION OF DELAWARE.

SPRING MATTRESS AND LIKE STRUCTURE.

Application filed June 7, 1924. Serial No. 718,443.

The invention relates more particularly to that class of mattresses and cushions in which a series of coil springs are employed, the object of the invention being to provide 5 improved means for holding the coil springs in proper relative position within the outer casing or sheath whereby the springs are inclosed. The invention consists in the novel features hereinafter described, illustrated in 10 the accompanying drawings and particularly pointed out in the claim at the end of this specification.

Figure 1 is a view in vertical section through a portion of a spring mattress or 15 cushion embodying my invention. Figure 2 is a plan view. Figure 3 is a detail view in vertical section on line 3—3 of Fig. 1. Figure 4 is a perspective view showing a suitable form of staple used for connecting cer- 20 tain parts.

The casing A that incloses the coil springs B will be of ticking or other suitable material and is shown surrounded by a pad or cushion C having a covering c, the pad C 25 being connected to the casing A by tufting cords D, in manner well understood by those familiar with this class of devices. The coil springs B are arranged in rows as shown in Fig. 2 of the drawing, and the top and bot- 30 tom terminal coils b of the springs B bear against the top and bottom walls a and a' of the casing A. Under the terminal coils b of the springs B extend strips of textile material, these strips being preferably 35 formed of heavy tape or webbing E and E' that cross each other at right angles, as clearly shown in Fig. 2 of the drawing. At points between the terminal coils of adjacent springs B the strips of webbing E and E' are securely 40 fastened to the adjacent walls a and a' of the casing A, preferably by means of staples F. Thus, by reference to Figs. 1 and 3 of the drawing, it will be seen that the top strips of webbing E' are secured to the upper wall 45 a of the casing A by the staples F, while the bottom strips of webbing E' are similarly attached to the bottom walls a' of the casing, the staples F in each instance uniting the strips of webbing E' to the walls of the cas- 50 ing at points between the terminal coils b of adjacent springs B. In like manner, the strips of webbing E will be united to the top and bottom walls of the casing A by the staples F, the staples F uniting the strips of 55 webbing E to the casing being arranged at

right angles to the staples that serve to connect the strips of webbing E' to the casing.

When the strips of webbing E and E' are united to the casing walls as last described, they serve to form with these walls pockets 60 for receiving and holding in place the terminal coils b of the springs B. To enable the terminal coils of the springs B to be inserted in their proper places between the strips of webbing E and E' and the walls 65 a and a' of the casing A, the terminal coils of the springs B will be slightly compressed so as to reduce their diameter, and also will be rotated slightly so as to permit their terminal coils b to be slipped between the broad strips 70 of webbing E and E' and the walls a and a' adjacent these strips of webbing and when the terminal coils have been inserted between the strips of webbing and the walls of the casing, the tension on the coils will be released and 75 they will be permitted to assume the position indicated in the drawing. When the coil springs have been thus placed in position for use, they will be securely retained against danger of accidental displacement and as well 80 also against danger of contact with each other.

Since the specific embodiment herein disclosed is merely illustrative of a single application of my invention, it will be understood that the scope of same should be determined by reference to the appended claim, 85 said claim being construed as broadly as possible, consistent with the state of the art.

Having thus described my invention, what 90 I claim as new and desire to secure by Letters Patent is:—

In a mattress or like structure, the combination of a mattress tick including top and bottom walls, a plurality of spiral coil springs 95 arranged within said tick so as to form two sets of parallel rows of springs, the rows of one set extending transversely of the rows of the other, and at substantially right angles thereto, each of the springs being common to 100 two relatively transversely extending rows and having their top and bottom end coils respectively disposed against the top and bottom tick walls, and means for maintaining the springs so arranged comprising a tape strip for each of said rows of springs, ex- 105 tending longitudinally thereof, inside and substantially diametrically of the end coils of the springs in the row, the strips for two relatively transversely extending rows in- 110

tersecting each other substantially axially of the spring common to the two rows and being fastened to the adjacent tick wall at points adjacent the outer peripheries of the end coils of such common springs, thereby forming with said tick wall, pockets for receiving the end coils and preventing contacting of the end coils of adjacent springs, the fastening

of said strips to the tick wall being relatively short crosswise of the strip so as to provide 10 a relatively wide space between the adjacent fastenings around each pocket, thereby permitting said end coils to be inserted into the pockets after the strips are fastened to the tick walls.

DON CARLOS TRAVIS.
